N. F. PRATT

OIL BURNER

Filed March 28, 1924

UNITED STATES PATENT OFFICE.

NORMAN FRANCIS PRATT, OF JACKSONVILLE, FLORIDA, ASSIGNOR TO GROVER CLEVE-
LAND STEMBERIDGE, OF JACKSONVILLE, FLORIDA.

OIL BURNER.

Application filed March 28, 1924. Serial No. 702,664.

To all whom it may concern:

Be it known that I, NORMAN F. PRATT, citizen of the United States, residing at Jacksonville, in the county of Duval and 5 State of Florida, have invented certain new and useful Improvements in Oil Burners; and I do hereby declare the following to be a full, clear, and exact description of the invention, such as will enable others skilled 10 in the art to which it appertains to make and use the same.

This invention relates to an improved construction of generator for oil-gas producer, and more particularly to a U-tube construction 15 of generator which admits the fuel at the end of one of the arms of the U-tube, and which has the generator nozzle or outlet disposed between the arms of the U-tube in such a manner that the oil gases find egress 20 from the generator through a final passage not in line with the projection of either arm.

An object of the invention is to provide a U-tube generator for oil-gas producers which will have a head in which is positioned a 25 Z-passage, said passage being so constructed that it will be a simple operation to thoroughly clean the generator nozzle and the several passages of the generator.

Another object of the invention is to provide 30 U-tube generator with a coiled wire wick within said tube in place of asbestos wicks formerly used.

The preferred form of generator is shown in the single figure constituting the drawing, 35 parts being shown in section.

My generator is formed with a head 1 which is of metal and which is provided with three parallel passages therethrough. The inlet opening into one arm of the U- 40 tube is screw threaded as at 2 and is adapted to receive a threaded plug 3, to which the intake or feed pipe 4 and couplings 5 are attached. The plug 3 is provided with a central passage 6 so that the fuel entering 45 through the said pipe will have a ready access through the same.

A U-shaped generator tube 7 is welded on to the head 1 and has an opening of corresponding diameter as the two outer passages 50 through the said head.

The threaded blank plug 8 is removably secured in the opposite side of the head 1 to seal the opening 9 through the said head.

The inner peripheries of both of the plugs 55 3 and 8 are shown as beveled and adapted to

seat on the correspondingly beveled seats in the passages at the opposite sides of the head. However, other means for making a tight joint may be employed.

A central opening 10 is formed through 60 the head 1 and is threaded at its inner end to receive the removable countersunk nozzle or orifice plug 11. Said passage 10 increases in size at its outer end and is interiorly screw threaded to receive the threaded valve casting or plug 12. A valve stem 13 is adapted to extend through the plug 12 and is threaded therethrough at 14. The inner end of the valve stem is of larger diameter than the outer end thereof and is adapted to have a 70 sufficient amount of adjustment, but will be non-removable from said plug when said plug is in its place in the generator. A music wire metal valve 15 is detachably secured at the inner end of the valve stem 13 75 and is adapted to extend through the nozzle or orifice plug to partially close the opening therein and to clean the opening when circumstances require. The outer end of the valve plug 12 is screw threaded and is provided with a countersunk outer end, and is adapted to threadedly receive the packing nut 16 which firmly and securely holds the packing 17 in place. The packing 17 may be of any desired material and can be readily renewed.

An operating lever 18 is secured at the outer end of the valve stem 13 for operating the same.

A clean-out passage 19 is formed diagonally between the passage 9 in the head 1 and the central valve passage 10, thereby forming with the said passages 9 and 10, a Z-passage. The passage 19 may extend through the wall of the passage 9 as at 20 95 to permit a cleaning instrument to be inserted in said passage without bending. However, the opening 20 may not be provided when the threaded extension of the passage 9 is made shorter, as will be readily understood. When the opening 20 is provided the blank plug will close the same as shown in the drawings.

I have provided coil wire wicks 21, which are adapted to be inserted in the opposite 105 arms of the U-tube 7, and serve to conduct by capillary attraction the fuel as it enters the intake, and to more quickly vaporize the same before it reaches the generator nozzle.

The diameter of the plug 3 will prefer- 110

ably be different from the diameter of the plug 8 so that the correct plugs will have to fit into the correct openings, thereby making this part of the fitting fool-proof.

5 The music wire 15 does not form a gas tight fit in the nozzle plug 11, but does so obstruct the passage through the nozzle that all the regulating of the flow of the generated gases can be done by manipulating the 10 valve stem 13 and so the valve controlling the flow of the fuel through the passage 4 is used only to either allow free passage of fuel or to shut it off entirely.

When it is necessary to clean the lamp 15 black or other obstruction from the generator, the plugs 3, 8 and 12 are removed and the cleaning is then readily accomplished.

It will be understood that I do not intend 20 to limit myself to the specific construction of the U-tube generator described in my specification, as many minor changes in detail of construction may be resorted to without departure from the spirit of the invention.

25 I claim:

1. In a liquid fuel burner, the combination of a U-shaped preheating tube adapted for connection at one of its ends to a source of fuel supply, a head having a passage extending therethrough, the other end of the tube being connected to one end of said passage, a fuel control passage extending through the head at one side of the afore-

said passage and parallel therewith, a valve 35 stem controlling the fuel passage, a third passage in said head extending obliquely from a point adjacent the discharge end of said fuel passage to the outer end of the first named passage, and a plug closing the outer end of said first named passage but not closing the said third passage, whereby when said plug is removed a cleaning instrument may be inserted into either of the said passages.

2. In a liquid fuel burner, the combination of a U-shaped preheating tube, a head to which the ends of the tube are attached, the head having passages therethrough in alignment with the arms of the said tube, means adapted to connect one of said passages with a source of fuel supply, a removable plug closing the outer end of the other said passage, a third passage through said head between the aforesaid passages and parallel therewith, a valve stem disposed in 50 said third passage adapted to control the discharge end thereof, and a fourth passage in said head extending obliquely from a point adjacent the discharge end of the said third passage to the outer end of that passage which is closed by a plug, said plug when removed permitting a cleaning instrument to be inserted directly into the obliquely extending passage.

In testimony whereof I affix my signature.
NORMAN FRANCIS PRATT:
